H. J. SCANLON,
ANNEALING POT CARRIAGE,
APPLICATION FILED APR. 19, 1921.

1,409,118.

Patented Mar. 7, 1922.

FIG. 1

FIG. 2

FIG. 3

UNITED STATES PATENT OFFICE.

HUGH J. SCANLON, OF WAYNESBURG, PENNSYLVANIA, ASSIGNOR TO AMERICAN STEEL COMPANY, OF PITTSBURGH, PENNSYLVANIA, A CORPORATION OF PENNSYLVANIA.

ANNEALING-POT CARRIAGE.

1,409,118.

Specification of Letters Patent.

Patented Mar. 7, 1922.

Application filed April 19, 1921. Serial No. 462,494.

To all whom it may concern:

Be it known that I, HUGH J. SCANLON, a citizen of the United States, and resident of Waynesburg, in the county of Greene and State of Pennsylvania, have invented a new and useful Improvement in Annealing-Pot Carriages; and I do hereby declare the following to be a full, clear, and exact description thereof.

10 My invention relates to an annealing pot carriage.

In a joint application filed of even date herewith by myself and Michael B. Kelly, Serial No. 462,525, we have illustrated and

15 described an annealing furnace for annealing wire or like products, and the invention there consisted in a long straight-away annealing chamber with the heating furnace at one side thereof and communicating therewith, the idea being to introduce the pots at the entrance end of the furnace and move them gradually toward the hottest part of the annealing chamber where the furnace is located and, then continue the 20 movement beyond the said furnace and gradually cooling the pots until the outlet is reached. The annealing carriages are connected up to form a train and are drawn through the annealing chamber by a chain

25 30 connected to the front carriage, and as the carriages leave the annealing chamber they are disconnected and lifted to one side to remove the pot and the carriage is then taken around to the entrance end of the annealing chamber and there connected up with the last carriage of the train, and in this way a continuous succession of carriages is kept moving through the annealing chamber.

35 40 The object of my invention is to provide a carriage for such annealing operation which will support the annealing pot securely in position during this passage through the annealing chamber, and of such construction that it will stand up against the severe heat to which such carriages are subjected in their passages through the annealing chamber, and at the same time provide convenient means for connecting and disconnecting the carriages as they enter and leave the annealing chamber.

To these ends my invention comprises the novel features hereinafter set forth and claimed.

In the drawing Fig. 1 is a side elevation 55 partly in section of a portion of the train composed of my improved carriages; Fig. 2 is a plan view partly in section; and Fig. 3 is a cross section of the annealing chamber showing my carriage therein. 60

In the drawing the numeral 2 designates the concrete foundation for the annealing furnace upon which the floor 3 is laid, said floor inclining slightly from the entrance to the discharge end of the annealing chamber 65 for facilitating the passage of the pots through the furnace, all as set forth and described in said prior application.

Located within the annealing chamber are the longitudinally extending troughs 4 containing the balls 5. The carriages, during their passage through the annealing chamber, are adapted to rest on said balls and move thereon, and I will now describe said carriages in detail. 75

Each carriage comprises a platform 6 with the ribs 7 formed thereon which form a rest or support for the annealing pot 8, which may be of any suitable construction. These ribs allow for the circulation of the heat 80 beneath the pot and give a more uniform quality of material.

The lower face of the platform is provided with the grooves 9 which register with the troughs 8 containing the balls 5. These 85 grooves extend the entire length of the platform and are brought adjacent to the platform of the next carriage, as clearly indicated in Fig. 2, so that the balls are confined for the entire length of the platform 90 and there is no opportunity for their escaping and falling on to the floor of the annealing oven and causing an uneven movement of the carriages.

The platform 6 has the enlargements 10 95 at the sides thereof with the upwardly projecting side lugs 11 which act as retainers for the pot 8 and prevent its shifting laterally. These enlargements act as feet upon which the carriage may rest when disconnected and deposited on the floor at one side of the furnace for the removal of the pot therefrom. These furthermore provide means for grasping the carriage for lifting it by means of a crane when it is removed 100 from the track, or when it is to be applied in position on the track to enter the annealing chamber. 105

To prevent the undue longitudinal shifting of the pot the platform 6 is provided at one end with the upwardly projecting lug 12 and at the opposite end with the hood 13. The lug 12 forms a hook for connecting up with the drawing chain 14, and when the carriages are connected together the hook portion 12 extends within the hood 13, as indicated in dotted lines, Fig. 1, and a coupling pin 15 passes through the clevis lug 16 and the lower portion 17 of the lug 12.

In making up the train at the entrance end of the annealing chamber, the chain 14 is connected up to the hook 12 of the first carriage, and a second carriage is then brought into position with its hook portion entering the hood 13, whereupon the coupling pin 15 is then inserted to form the connection, and in this manner the train is gradually made up and is drawn through the annealing chamber. Where the track is slightly inclined from the entrance to the discharge end of the annealing chamber, the power required to draw the train is reduced, and when the discharge end is reached the chain 14 is released from the hook 12 and the coupling pin 15 is removed, whereupon the crane is brought into position to grasp the carriage at the enlargements 10 to lift the carriage and the pot from the track to the floor, the enlargements 10 forming the feet on which the carriage rests. In this

position the annealing pot is removed and the carriage is then picked up and moved to the entrance end of the furnace, where it is connected up to the train in the manner aforescribed, and the pot is inserted and it proceeds through the entrance in the usual way.

The ribs 7 add strength to the carriage and at the same time permit the air to circulate under the pot, giving a more uniform heating, and the pot, when once centered, is held from shifting by the retaining lugs 11 at the sides and the hook 12 and hood 13 at the ends.

What I claim is:

1. A carriage for annealing pots comprising a platform having enlargements at the sides thereof forming feet for same, and upwardly extending lugs on said enlargements to prevent the lateral shifting of the pot.

2. A carriage for annealing pots comprising a platform, a hook portion at one end of said platform, a hood at the opposite end of said platform with openings formed therein for the insertion of a coupling pin.

In testimony whereof, I, the said HUGH J. SCANLON, have hereunto set my hand.

HUGH J. SCANLON.

Witnesses:

ROBT. D. TOTTEN,
JOHN F. WILL.
